UNITED STATES PATENT OFFICE.

JOHN M. RILEY, OF NEWARK, NEW JERSEY.

FASTENING FOR DOG-COLLARS.

SPECIFICATION forming part of Letters Patent No. 394,506, dated December 11, 1888.

Application filed February 27, 1888. Serial No. 265,631. (No model.)

To all whom it may concern:

Be it known that I, JOHN M. RILEY, a citizen of the United States, residing at Newark, New Jersey, have invented certain new and useful Improvements in Dog-Collar Fastenings or Catches; and I do hereby declare the following to be a full, clear, and exact description of the invention, reference being had to the accompanying drawings, which form part of this specification.

My invention has relation to dog-collars, and has for its object the provision of a novel, simple, and easily-operated clasp or catch for adjustably securing the collar upon the animal's neck.

My invention consists in the novel construction, combinations, and arrangement of parts hereinafter described and specifically claimed.

Referring to the accompanying drawings, Figure 1 is a top view, and Fig. 2 a vertical longitudinal sectional view, of a dog-collar catch or clasp constructed according to my improvements. Figs. 3 and 4 are longitudinal sectional views of modified forms of the same. Fig. 5 is a transverse sectional view of the clasp shown in Figs. 1 and 2, and Fig. 6 is a similar view of the modified form shown in Fig. 4.

A designates a flat rectangular metallic casing, which forms the body of the clasp, and which is open at one end, C, to receive a tongue, B, the body A and tongue B being secured, respectively, to the ends of the dog-collar. The casing A is provided with an open-ended slot, D, and said slot D has notches *d d* at intervals on its sides. The tongue B carries a vertical stud, E, the shank of which is diminished in width near the top,

as at *e*, so as to allow the stud when in one position to slide readily through the slot D, while the base of said stud is of such width that it will not pass through the narrower portion of the slot D, but will fit in the notches *d d* of the same when the stud is in another

position. Upon the back of the tongue B is a spring, F, which tends to press said tongue

against the side of the casing having the slot D, and thus project the stud E through the notches *d d*.

To operate the catch constructed as above described, it is only necessary to press upon the stud E until the narrow portion *e* of its shank is in line with the slot D and the wider part or base of said shank is out of engagement with the notches. The tongue B is now slid along in either direction until the desired point of adjustment has been reached, whereupon the pressure upon the stud E is released and the stud is allowed to rise and project its wider portion through notches *d d*, as before.

In the modified form shown in Figs. 3 and 4 the stud E is secured to a spring, F, upon the bottom of the casing A, and projects through holes in said casing. The open-ended slot D and the notches *d d* are in this form of the device in the tongue B, instead of being in the casing A. The operation of the modified device is substantially the same as that of the one above described—that is, to adjust the catch the stud E is pressed down until the narrow part *e* of its shank is presented to the slot D in the tongue B, and the latter is slid into or out of the casing A to secure the desired adjustment, and the stud E is then allowed to rise until its base or wider part projects into the notches *d d*, as before described.

Having described my invention, I claim—

In a catch or fastening, the combination of the frame A, having slot D, with notches *d d*, and a tongue, B, having stud E, with narrowed shank *e*, and a spring, F, attached to the lower side of said tongue, substantially as shown and described.

In testimony that I claim the foregoing I have hereunto set my hand this 17th day of January, 1888.

JOHN M. RILEY.
